UNITED STATES PATENT OFFICE.

HARRY J. BLOOM AND ABRAHAM SLATIS, OF NEW YORK, N. Y.

DESIGN FOR A RING.

Application filed March 13, 1925. Serial No. 12,707. Term of patent 3½ years.

To all whom it may concern:

Be it known that HARRY J. BLOOM and ABRAHAM SLATIS, citizens of the United States, residing at New York, in the county of New York and State of New York, have invented a new, original, and ornamental Design for Ring, of which the following is a specification, reference being had to the accompanying drawing, forming part thereof.

In the drawings:—

Figure 1 is a plan view of the ring developed on a plane to more clearly bring out the appearance of the top as a whole.

Figure 2 is a side elevation.

We claim:—

The ornamental design for a ring as shown.

HARRY J. BLOOM.
ABRAHAM SLATIS.
